To all whom it may concern:

Be it known that we, FREDERICK KAMPFE, RICHARD KAMPFE, and OTTO KAMPFE, citizens of the United States, and residents of Brooklyn, in the county of Kings and State of New York, have invented a new and original Design for Safety-Razor Casings, of which the following is a specification.

In the drawing, A is the casing, B the guard, and C the apertured teat or projection.

We claim—

In testimony that we claim the foregoing as our invention we have signed our names, in presence of two witnesses, this 25th day of March, 1896.
